[57] CLAIM

The ornamental design for a combined power outlet and meter support box, substantially as shown and described.

DESCRIPTION

FIG. 1 is a front elevational view of a combined power outlet and meter support box showing my new design with the lower front cover in raised position.

FIG. 2 is a rear elevational view thereof.

FIG. 3 is a side elevational view with the front cover in closed position, the opposite side being a mirror image of the same.

FIG. 4 is a bottom plan view of FIG. 1.

FIG. 5 is a top plan view of FIG. 1.

FIG. 6 is a front elevational view of the combined power outlet and meter support box with the lower front cover closed.

FIG.1.

FIG.2.

FIG.3.

FIG.4.

FIG.5.

FIG. 6.
